H. M. GREEN.
WELL CLEANING DEVICE,
APPLICATION FILED DEC. 26, 1917.

1,279,333.

Patented Sept. 17, 1918.

UNITED STATES PATENT OFFICE.

HENRY M. GREEN, OF KANSAS CITY, MISSOURI.

WELL-CLEANING DEVICE.

1,279,333.

Specification of Letters Patent. Patented Sept. 17, 1918.

Application filed December 26, 1917. Serial No. 208,970.

To all whom it may concern:

Be it known that I, HENRY M. GREEN, a citizen of the United States, residing at Kansas City, in the county of Jackson, State of Missouri, have invented certain new and useful Improvements in Well-Cleaning Devices, of which the following is a full and exact specification.

This invention relates to devices for cleaning out wells of comparatively small diameter, such as oil wells, which require the occasional use of some means for removing the sand, dirt and the like from the bottom of the well. The present invention aims to employ a flow of water for this purpose directed through the pump tubing of the well. The primary object of the invention, therefore, is to provide a simple device adapted to be attached to the pump tubing and constructed to produce and maintain a vigorous whirling action of the water at the points from where the sand and the like are to be removed.

It is further sought to devise a construction which will operate to aid in the feeding movement of the apparatus through the material as it is removed.

With these general objects in view, the invention will now be described with reference to the accompanying drawing wherein is illustrated a practical form of construction for embodying the improvements, after which the novel features thereof will be particularly specified in the appended claims.

35 In the drawing—

Figure 1 is a sectional elevation showing a well casing provided with a cleaning device or pump attachment constructed in accordance with the present invention;

40 Fig. 2 is a vertical sectional view of the cleaning device, taken on the line 2—2 of Fig. 1 and looking in the direction of the arrow in the latter view; and

Fig. 3 is a transverse section, taken on the line 3—3 of Fig. 1.

Referring to the drawing in detail, a portion of a well casing 4 is shown, within which is positioned a pumping tube 6 to the lower end of which is designed to be removably connected the pipe section 8 of the cleaning attachment, the section 8 forming an extension of the tubing 6 and connection thereto being suitably made by means of a coupling 10. Attached to the sides of the pipe section 8 is a series of elbow discharge tubes 12 serving as water ejecting elements

in communication with the interior of said pipe section. The tubes 12 are arranged in spiral relation around the pipe section 8 and with their outer end portions extended in approximately tangential relation to the outer surface of said pipe section. The outer ends of the tubes are also turned in the same general circumferential direction (see Fig. 3) with reference to the pipe section in order that the jets of water discharged from the tubes will combine to produce a whirl of water having the same general direction circumferentially about the said pipe section. Some of the tubes 12 will be positioned approximately horizontal, as at the middle of the pipe section 8, while above and below the horizontal tubes the other tubes will preferably be turned slightly upward and downward, respectively (Figs. 1 and 3) for the purpose of producing jets discharged in somewhat diagonal directions while at the same time maintaining the same general circumferential movement of the whirl of water within the casing 4, these diagonal jets serving to increase the effectiveness of the cleaning operation. The number of tubes 12 and the combined area of their cross-sections will also be such as to approximately equal the cross-sectional area of the pipe section 8, or may be somewhat less than said cross-sectional area of the pipe section 8 in case it should be desired to increase the force of the jet action through the tubes 12.

Threaded to the lower end of the pipe section 8 and fixed thereto by means of a pin 14 is a foot-piece 16, which is recessed, as at 18, in its upper face, its bottom face being of inverted-cone shape, whereby the foot-piece is adapted to settle readily through the deposits of material to be removed by the action of the device.

In the operation of the device, the pump tubing is taken up out of the well in order to replace the usual pump cylinder or working barrel of the pump with the cleaning attachment, which is secured in place by means of the union or coupling 10. The pump tubing is then again lowered into the well casing 4 until the foot-piece 16 reaches the material to be cleaned out of the bottom of the well and settles in said material until the attachment becomes partially embedded therein. Water is driven by any suitable means down through the tubing and obviously is ejected in approximately tangential jets through the tubes 12 into the

space between the attachment and the casing 4, and thereby produces a vigorous whirling motion of the water in said space. Some of the water will pass down around the foot-
 5 piece and act to loosen up the dirt and sand material around the same and thus promote the feeding action of the device, which action is of course further facilitated by the conical form of the foot-piece. Further, the
 10 water around the attachment is soon charged with the material, and this, being more or less gritty, the whirling of the water charged with such grit rapidly cuts and eats its way through the remaining deposits of material.
 15 A continuous stream of the water, carrying away the material which becomes suspended therein, is driven by the pressure from within the pump tubing and attachment on up within the casing 4 and around the exterior
 20 of the pump tubing 6 to the top of the well; the whirling motion of the water, as well as its advance movement (which would be otherwise retarded on account of the larger cross-sectional area outside the attachment),
 25 is constantly maintained, however, around the attachment by the construction and arrangement of the tubes 12.

It will thus be apparent that an extremely simple means is provided for effectively
 30 loosening up the deposits and thoroughly cleaning and scouring out the bottom of the well by means of a whirling water flow, and that the device comprises a very inexpensive form of construction that is both economical and efficient in its operation. While the structure shown and described constitutes a satisfactory and practical embodiment of the improvements, the right is reserved to all such formal changes or modifications as may
 35 fairly fall within the scope of the claims appended hereto.

What I claim is:

1. Means for cleaning out the bottoms of wells and adapted for attachment to pumping tubes, comprising a pipe section having means for attachment to the bottom of the pumping tube and within the well casing, said pipe section being provided with lateral water discharge passages extending outward
 45 and arranged to discharge jets of water from said pipe section into the space between said pipe section and the well casing and approximately tangentially to the outer surface of said pipe section for producing a whirl of
 50

water in the same general circumferential 55 direction within said casing.

2. Means for cleaning out the bottoms of wells and adapted for attachment to pumping tubes, comprising a pipe section having means for attachment to the bottom of the pumping tube and within the well casing, and jet tubes carried by said pipe section and forming outlets therefrom into the space between said pipe section and well casing, the discharge ends of said jet tubes being turned in position to discharge approximately tangentially to the outer surface of said pipe section and produce a whirl of water in the same general circumferential 60 direction within said casing.

3. Means for cleaning out the bottoms of wells and adapted for attachment to pumping tubes, comprising a pipe section having means for attachment to the bottom of the pumping tube and within the well casing, and jet tubes carried by said pipe section and forming outlets therefrom into the space between said pipe section and well casing, the discharge ends of said jet tubes being turned in position to discharge approximately tangentially to the outer surface of said pipe section with some of said discharge ends 65 extending diagonally downward and others diagonally upward and all pointing in the same general circumferential direction with reference to said pipe section, whereby a circumferential whirl of water is produced around said pipe section within said well casing.

4. Means for cleaning out the bottoms of wells and adapted for attachment to pumping tubes, comprising a pipe section having means for attachment to the bottom of the pumping tube and within the well casing, said pipe section being provided with lateral water discharge passages extending outward and arranged to discharge jets of water from said pipe section into the space between said pipe section and the well casing and approximately tangentially to the outer surface of said pipe section for producing a whirl of water in the same general circumferential direction within said casing, and a foot-piece of inverted-cone shape secured to the lower end of said pipe section.

In witness whereof I affix my signature.

HENRY M. GREEN.
